UNITED STATES PATENT OFFICE.

EMMANUEL DOBROWSKY, OF NEW YORK, N. Y., ASSIGNOR, BY DIRECT AND MESNE ASSIGNMENTS, TO MOTOR CAR ADVERTISING DEVICE CO., INC., OF NEW YORK, N. Y., A CORPORATION OF NEW YORK.

TAXI ADVERTISING DEVICE.

Application filed July 6, 1925, Serial No. 41,819. Renewed January 13, 1927.

This invention relates to taxi advertising devices and more particularly to an advertising device especially adapted to be positioned within a taxicab, bus, or other public 5 automobile conveyance which is operated through the medium of the engine.

A further object is to provide an advertising device which can be conveniently observed or read by the occupant on the seat 10 of the car, and which will be entirely automatic in its operation and the movement of one advertisement, sign or data of any sort.

A further object is to provide an apparatus of this character which is operated by 15 suction or partial vacuum induced by the engine of the taxi or other automobile, which will be neat and attractive in appearance, and which can be manufactured and sold at a reasonably low price.

With these and other objects in view, the invention consists in certain novel features 20 of construction and combinations and arrangements of parts, which will be more fully hereinafter described and pointed out 25 in the claim.

In the accompanying drawings—

Figure 1 is a fragmentary view in side elevation of a taxicab partially broken out, illustrating the position of my improved 30 advertising device;

Figure 2 is a view in longitudinal section with my improved device removed from the taxicab, this view being taken on the line 2—2 of Figure 3;

Figure 3 is a view in elevation, looking at the left-hand end of Figure 2;

Figure 4 is a view, illustrating the power driven roll and its adjacent mechanism, the casing being in section;

Figure 5 is a view in section on the line 5—5 of Figure 4.

Figure 6 is a fragmentary view in longitudinal section illustrating the valves 28 and 35 in their mounting.

1 represents a taxicab and it is distinctly understood that my invention is particularly adapted for use in combination with a taxi and I desire to cover the combination broadly of my improved apparatus or device which is especially designed for use in connection with a taxicab.

2 represents the casing of my improved apparatus, which may be secured in the

upper front portion of the body of the taxicab in any approved manner.

In this casing 2 I provide a series of rolls 3 and 4. I have shown three rolls 3 in the upper portion of the casing and a single roll 4 in the lower portion of the casing although it is obvious that any desired number and arrangement of rolls may be provided.

On these rolls 3 and 4 and over a smaller idle roll 5, a pair of endless tapes 6 is mounted, and on these tapes, sheets or aprons 7 may be secured containing advertising or other matter to be displayed. It is of course to be understood that the sheets or aprons 7 may be removable and replaced as occasion may require, and I do not wish to be limited to the particular mounting of the advertising or display matter.

In the wall of the casing 2 I provide a transparent window 8 which is in line with the vision of the passenger on the seat of the taxi so that the advertising or display features may be readily observable through this window.

To illuminate the same, especially at night I provide an electric lamp 9 located within a reflector 10 which throws the light through 80 the window onto the advertising or display matter.

The driving roll 4 as well as all of the other rolls are preferably mounted so as to reduce friction to a minimum, and I have 85 illustrated in Figure 4 this roll as having pointed trunnions 11 to turn in thrust bearings 12. I also provide small, preferably rubber-covered, pressure rollers 13 mounted in pivoted arms 14, the latter engaged by 90 springs 15 to hold the rollers 13 against the tapes 6, or advertising matter on the tapes, so as to prevent slipping of the endless advertising matter, as will be readily understood.

A ratchet wheel 16 is fixed to turn with the drive roll 4, and a spring-pressed pawl 17 engages this ratchet wheel to prevent retrograde movement thereof. Forward movement is imparted to the ratchet wheel 16 by a spring-pressed pawl 17 carried by a frame 18. This frame 18 is of general oblong shape with its ends projecting into cylinders 19 and 20 and fixed to the pistons 21 and 22 in the respective cylinders, so that the 105 pistons and the cylinders constitute a rigid

movable fixture which is movable as an entirety, as will be explained.

Between the cylinders 19 and 20 a head 23 is formed and has a passage 24 connecting the two cylinders. Valve seats 25 are formed at both ends of the passage 24 and valves 26 and 27, respectively, are adapted to engage and close said ports. The valves 26 and 27 are connected by a stem 28 which is longer than the passage 24 so that only one of the valves 26 or 27 can be seated at a time, the other being open.

The passage 24 communicates centrally with a passage 29 which latter communicates with the bore of a nipple 30, the latter being connected by a coupling 31 with a tube 32, which may be flexible if desired.

As shown most clearly in Figure 6, the head 23 between the cylinders 19 and 20 is provided with a passage 33 communicating with both cylinders 19 and 20 and having valve seats 34 at its respective ends adapted to be engaged by a valve 35 shorter than the passage. This passage 33 communicates with the atmosphere through the medium of a port 36 and has pins or projections 37 at its ends which project into the respective cylinders not enough to be engaged by the respective plungers. When one piston moves to its extreme inward position it will shift this valve to the other extreme position of the valve, and this valve as well as the valves 26 and 27 will be held by the suction or partial vacuum created within the cylinders until said valves are forcibly shifted from one position to another by engagement with the plungers. By reason of this valve 36 air is admitted to the respective cylinders as the plungers move outwardly.

It is to be understood that this tube 32 is adapted to be connected with the exhaust or other portion of the taxi engine which induces a suction or partial vacuum as the apparatus is operated by suction or partial vacuum, as will now be explained.

With the parts as shown in Figure 5, the suction in cylinder 19 is drawing the piston 21 downwardly, imparting a corresponding movement to the pawl 17 which contacts with the teeth on the ratchet wheel 16 and imparts rotation thereto. This downward movement of the piston 21 will continue until the piston strikes the valve 26 and forces it downwardly to closed position. This will open the valve 27 and the suction will then be in the cylinder 20 between the piston 22 and the head 23 so as to move the frame 18 in the opposite direction. When frame 18 moves in the opposite direction the pawl 17 rides over the teeth of the ratchet wheel 16 without imparting any movement thereto.

It is to be understood that in the claim which follows hereinafter I shall refer to the tapes and their sheets or aprons as an "endless advertising container", using this term in its broadest possible sense to include any movable advertising member that may be moved by motion imparted to the roll 4.

I would also have it distinctly understood that I desire to cover broadly the idea of a display or advertising device of this character, in combination with a taxicab or analogous vehicle, and I do not wish to be limited to the specific details set forth but consider myself at liberty to make such slight changes and alterations as fairly fall within the spirit and scope of the appended claim.

I claim:

An advertising device adapted to be located in the body of a closed motor vehicle, and comprising a casing having a window therein, a reflector adjacent the window, an electric light in the reflector, an endless display device in the casing, a roller transmitting motion to the endless device, and a suction operated engine controlling the movement of said roller and endless device.

EMMANUEL DOBROWSKY.
